UNITED STATES PATENT OFFICE.

GEORGE L. PRICHARD, OF PORT ARTHUR, TEXAS, ASSIGNOR TO GULF REFINING COMPANY, OF PITTSBURGH, PENNSYLVANIA, A CORPORATION OF TEXAS.

PROCESS OF DISTILLATION AND APPARATUS THEREFOR.

1,264,435.

Specification of Letters Patent.

Patented Apr. 30, 1918.

Application filed June 28, 1916. Serial No. 106,401.

To all whom it may concern:

Be it known that I, GEORGE L. PRICHARD, a citizen of the United States, residing at Port Arthur, in the county of Jefferson and 5 State of Texas, have invented certain new and useful Improvements in Processes of Distillation and Apparatus Therefor, of which the following is a specification.

This invention relates to processes of distillation and apparatus therefor; and it comprises a method of obtaining uniform cuts or fractions and products from petroleum naphtha and similar distillates wherein such a distillate is redistilled with 15 the aid of steam heat in a plurality of successive stills operating in series as regards the material to be distilled, the liquid being submitted to a prolonged and methodical evaporative treatment in each such still and 20 the vapors from each such still being thoroughly dephlegmated with the aid of inflowing liquid, and the residual oil discharged freed from the oils of the several distillates, and it also comprises an assemblage of apparatus elements useful in the 25 performance of such process and comprising a plurality of steam heated stills arranged for successive treatment of naphtha or the like, each such still being arranged to 30 distil liquid passing in transit therethrough in a comparatively long path and each being provided with means for thorough dephlegmatory exchange between the vapors therefrom and the liquid fed thereto; all as more 35 fully hereinafter set forth and as claimed.

In the manufacture of distilled commercial products from petroleum, it is customary to take off and condense a product called "crude naphtha." This crude naphtha is afterward redistilled with the aid of 40 steam for the preparation of various naphtha products or naphthas of different gravities; which, for lack of better names, may, beginning with the lightest, be called gasoline, naphtha and benzin. In the still remains a comparatively high boiling residual oil which is the equivalent of the ordinary 45 kerosene distillate. In this distillation heat is usually furnished by blowing free steam into the still through perforated pipes arranged near the bottom of the still. Sometimes the heat of steam coils is resorted to for distillation (close steam). The distillation is ordinarily in a single still which is 50 progressively raised in temperature with

separate collection of the condensates or "cuts" coming over at desired temperature intervals. This operation is of course intermittent, and it is difficult to secure as uniform products in a single operation as is 55 desirable. If the operation be so conducted as to give properly separated distillates the quality of the residual oil (kerosene) suffers and on the other hand if the operation be so conducted as to give a satisfactory residual oil the quality of the distillates is not so good. And in any event the several fractions or cuts are not well separated from each other.

In the present invention I have devised a 70 method and provided an apparatus adapted for making such a separation as that above indicated, obtaining better distilled products in the sense of materials having narrower range of boiling points and being to that 75 extent much more definite than those usually obtained in redistilling the crude naphtha while also giving a good quality residual oil (kerosene). For this purpose, instead of using a single still and collecting the 80 various fractions or cuts from it successively, I distil the liquid, so to speak, in transit, using a plurality of stills, each of which is adapted to furnish a single cut and passing the flowing liquid which supplies 85 this still in a countercurrent against the vapors coming from such still. The liquid flows through the plurality of stills in succession, the liquid from the first such still being supplied in countercurrent against the 90 vapors coming from the second such still and so on. And I provide the interior of each such still with baffles or similar devices adapted to cause the liquid introduced at one end of the still to travel progressively 95 toward the other end of the still. The undistilled residual oil finally discharged is freed of all oils volatile at the temperatures employed in distillation.

While I may use any type of steam heated 100 still and arrange these stills in any desired manner, yet I find it better to use a certain particular construction and relation of the several stills and their settings. I find that it is desirable to superimpose the several 105 stills in vertical arrangement as this gives convenience in operation and connections. When so superimposed, the stills may be supported in any of the ordinary types of setting, but I find it better to use a special 110

steel skeleton frame carrying supporting cradles, etc. and a special type of heat insulation for each still (see the application of Herbert Henderson Serial No. 84180, filed March 14, 1916). In so arranging the stills, a steel skeleton frame is employed and the several stills are supported therefrom on cradles while each still is provided with heat insulation in a special manner; being covered with an outer layer of heat insulating material at its top and an inner layer of heat insulation at the bottom. The upper layer of heat insulation may be supported on suitable angle irons projecting from the sides of the still bodies which may be, as usual, horizontal steel cylinders. Arranging the insulation in this manner renders detection of leakage, repairs, etc. easily practicable.

I shall hereinafter describe my process and organization of apparatus elements as applied to the manufacture of three different cuts from a petroleum product of the nature of the crude naphtha described, it being understood that I may use two such stills or more than three without departing from the principles of my invention. In such an organization, I mount the three stills one above the other with the still operating at the lowest temperature at the top. Each of the stills communicates with its own tower or dephlegmatory column which may be provided with internal baffles or shelves. For structural convenience, I may mount these three columns in the form of a single column divided by suitable partitions at proper points. The incoming liquid is supplied to the top of the sub-tower connected with the first or topmost still and passes downward through this sub-tower against the vapors passing upward therethrough from the still until the liquid reaches the bottom of the sub-tower whence it is supplied into the still. The residual liquid coming from this first still is similarly supplied to the sub-tower of the next succeeding still; and from the second still the residual liquid similarly goes to the third still. High test residual oil thoroughly freed of matters volatile at the temperatures employed, is withdrawn from the last still in the series and cooled in any suitable manner. Although special film-evaporating stills may be employed, I find it desirable to use stills of the ordinary cylindrical shape but each provided with a plurality of baffle plates to give a circuitous liquid flow therethrough. Three baffles may be used in each still. The vertical arrangement of the stills with the fresh liquid supplied at the top allows feed through the system to be by gravitation.

In the accompanying illustration I have shown, more or less diagrammatically, certain embodiments of apparatus elements

within the present invention and suitable for the performance of the stated process. In this showing:

Figure 1 is an end elevation, certain parts being in section, and

Fig. 2 is a side elevation, certain elements being in section.

In this apparatus as shown, three steam stills, A, B and C, are shown mounted in superimposed arrangement. As shown, the still having the lowest temperature, A, is uppermost, while that having the highest temperature, C, is lowermost, so that the liquid may flow downward through the system by gravitation. As shown, these stills are mounted on a steel framework 1, provided with suitable cradles 2, supporting members 3, etc. The necessary heat insulation for the stills is provided, in the type of still shown, by an upper outer layer 4 of radial tile or other suitable material supported on angle irons 5. In the interior, at the bottom portion of the still, may be another layer of heat insulating material 6. This arrangement is convenient for a number of reasons.

As shown each still is provided with its own dephlegmating column and these dephlegmating columns for structural reasons are made one continuous structure; the three sections being mounted in superimposed relation as one continuous column. From still A vapors are led outward through vapor line 7 entering at the base of section 8. As shown this column is provided with plates 9 of a usual type. Any other kind of filling and film-forming material or structure may be employed in its lieu. Passing upwardly through the columns past these plates the vapors go to vapor outlet 10, whence they are led to any suitable condenser (not shown). Liquid is introduced into the top of the column at 11 through heat exchanger 12, and may, as shown, pass in countercurrent to and be warmed by the outgoing vapors which pass outward through vapor outlet 10 to any suitable condenser (not shown). The incoming liquid passes downward through the column-section 8 from plate to plate, exchanging heat with the upward passing current of vapor and finally reaches bottom 13 of the column, whence it is led into the still through feeding conduit 14. The bottom 13 forms the top of the next section 15. This section is also provided with plates or the like and receives vapors from B through vapor line 16. The vapors pass upwardly against downflowing liquid coming from the previous still A through overflow line 17. The liquid after passing through this section and being enriched by condensed vapors passes into B through feed line 17'. From B residual liquid passes through overflow line 18 to the top of the lowermost section 130

19 and passes downward therethrough over the plates and against the vapors going through 20 from still C. At the bottom of the column liquid passes through 21 into 5 still C.

Within, the stills are generally provided with the usual steam introduction means 23 and (see Fig. 2) internal baffles 24, 25 and 26, adapted to cause a tortuous flow of 10 liquid from end to end of the still. As may be seen by Fig. 2, the liquid to be distilled enters at one end of the still and leaves at the other, flowing past the stated baffles. The vapors from the second section (15) 15 pass to any suitable condenser (not shown) through vapor outlet 27 and those from the lowermost section (19) through vapor outlet 28.

From the lowermost or hottest still C the 20 thoroughly exhausted liquid is led to a suitable cooler through outlet 29. The hot liquid may be led through heat interchanger 29' to heat the oil supplied to the system (through 11). Pipes 31, 32 and 32' connect 25 stills A, B and C, respectively, to a riser 30, leading to a pump (not shown). This construction permits the oil to be pumped from the stills for repairs and like purposes. Connections 33, 34 and 35 allow draining off. 30 condensed water from A, B and C, respectively into funnel connections 33', 34' and 35' which connect to the sewer line 36. The funnel connections allow the operator to determine when the water has been drawn entirely from the still. 35

In the use of the described structure, crude naphtha is allowed to flow in through inlet 11 and is warmed in heat interchangers 29' and 12. It flows downwardly over the 40 plates 9 until it reaches still A through 14. In so passing it gives up vapors of low boiling materials to the vapors from 7 and itself condenses higher boiling portions of such vapors so that the distillate obtained by condensing the vapors from 10 is a uniform 45 gasoline of good quality. In still A the incoming liquid is delivered at one end of the still and passes slowly toward the other end past the baffles and is thoroughly freed of 50 its low boiling constituents in so passing. At the time it reaches line 17, it has been thoroughly freed of the grade of naphtha called gasoline. From 17 it flows down through section 15 against the upwardly 55 passing vapors from B and dephlegmates these vapors in a similar way until it reaches still B through line 17'. Here it passes from end to end of the still in a similar manner until it flows outwardly at 18. In so flowing, the second component of the crude naphtha, which may be here called naphtha, furnishes vapors which in going through 60 section 15 are thoroughly dephlegmated giving a uniform cut in the condenser (not 65 shown). The outflowing liquid from B

passing through 18 into the lowermost section 19, flows downwardly therethrough against the vapors passing from C and it finally reaches C through inlet 21. The vapors from C passing through 20 and 19 70 to exit at 28 are condensed to form benzin. After flowing through still C the liquid withdrawn at 29 and cooled in any suitable device (not shown) is an oil which is equivalent to or is a high grade kerosene distillate. 75

The treatment of crude naphtha in the manner just described is one exemplification of my invention which may be applied to other distillates and oils than such crude naphtha; and I may in treating crude naphtha use only two stills or more than three stills, the number shown. I regard my invention as being applicable to cases where it is desired to steam-distil petroleum distillates in order to obtain a plurality of 80 uniform cuts or fractions with a uniform undistilled high boiling residual oil or fraction.

It will be obvious that with the present method I have devised a way of distillation 90 in which with a comparatively cheap construction, I can separate a given amount of crude naphtha into gasoline, naphtha and benzin with a comparatively small amount of steam, and with a saving of time. The 95 several distilled products obtained are of uniform quality and do not need redistillation. In one operation, I am obtaining gasoline, naphtha and benzin with closer boiling points. There is also a saving in the 100 amount of condenser water necessary and a saving in the amount of ground space required.

What I claim is:—

1. The process of continuously redistilling 105 petroleum products which comprises passing a continuous current of a petroleum oil to be distilled through a plurality of successive stills, each such still being provided with a vapor outlet and dephlegmating column, and 110 the liquid supplied to each such still first passing through such dephlegmating column, and the liquid in each such still being caused to flow from end to end thereof in a more or less tortuous passage for the purpose 115 of complete exhaustion therein.

2. The process of continuously redistilling crude naphtha for the purpose of making 120 definite cuts or fractions therefrom which comprises continuously supplying such crude naphtha to and through a plurality of stills in series, the oil feeding each such still being passed in contact with the vapors from such still prior to entering the still and the oil in the still being caused to flow from end to 125 end of such still in a more or less tortuous passage.

3. The process of continuously distilling 130 petroleum products which comprises passing a continuous current of petroleum oil to be

1
distilled through a plurality of successive stills, the vapors from one still being conducted past and contacted with the oil from another still outside of said stills and the 5 said oil being delivered from said outside source to the still the vapors from which it has passed.

4. The process of continuously distilling petroleum products which comprises establishing and maintaining a plurality of stills 10 operating in series, passing the oil from one still outside of said still and in countercurrent to the vapors from another still, and then passing said oil into said second still.

15 5. In a petroleum still, the combination of a plurality of steam heated stills arranged in series for the flow of liquid therethrough, each such still being provided with a dephlegmating column with the feed of liquid 20 to each still through such dephlegmating column, the liquid flowing from each preceding still passing through the dephlegmating column of the next succeeding still, and each such still being provided with means for 25 causing a flow of liquid in a tortuous path from end to end of the still.

6. In a petroleum still, the combination of a plurality of steam heated stills arranged in series for the flow of liquid therethrough, 30 each such still being provided with a dephlegmating column with the feed of liquid to each still through such dephlegmating column, the liquid flowing from each preceding still passing through the dephlegmating column of the next succeeding still, each 35 such still being provided with means for

causing a flow of liquid in a tortuous path from end to end of the still, and such plurality of stills being mounted in vertical arrangement so that the flow of liquid from 40 still to still may be downward through the series.

7. In a petroleum still the combination of a plurality of heated stills arranged in series for the flow of oil therethrough, each still 45 being provided with means for delivering vapor therefrom and returning condensed liquid thereto and a dephlegmating column for each still, and connections arranged for delivering oil from one still to a succeeding 50 still in the series past the vapors rising from such succeeding still.

8. In a petroleum still the combination of a plurality of heated stills arranged in series 55 for the flow of oil therethrough, each still being provided with means for delivering vapor therefrom and returning condensed liquid thereto, and connections arranged for delivering oil from one still to a succeeding 60 still in the series past the vapors rising from such succeeding still, and means for separately withdrawing and collecting the vapors from each still after such vapors have been contacted with the oil being delivered by the preceding still.

In testimony whereof, I affix my signature hereto.

GEORGE L. PRICHARD.
